UNITED STATES PATENT OFFICE.

ALAN ROBB FERGUSSON, OF NEW YORK, N. Y.

LOCK FOR SAFETY-DEPOSIT BOXES.

SPECIFICATION forming part of Letters Patent No. 663,876, dated December 18, 1900.

Application filed February 13, 1900. Serial No. 5,078. (No model.)

To all whom it may concern:

Be it known that I, ALAN ROBB FERGUSSON, of New York, in the county of New York and State of New York, have invented certain new and useful Improvements in Locks for Safety-Deposit Boxes; and I do hereby declare the following to be a full, clear, and exact description of the invention, such as will enable others skilled in the art to which it appertains to make and use the same.

My invention relates to an improvement in locks, and more particularly to such as are adaptable for use on the doors of safe-deposit boxes, the object of the invention being to provide a simple lock capable of operation only by means of two keys and which shall be so constructed as to effectually prevent picking.

With this object in view the invention consists in certain novel features of construction and combinations and arrangements of parts, as hereinafter set forth, and pointed out in the claims.

In the accompanying drawings, Figure 1 is a face view of a safety-deposit box to the door of which my improved lock is applied. Fig. 2 is a sectional view on the line *x x* of Fig. 6. Fig. 3 is a sectional view on the line *y y* of Fig. 6. Fig. 4 is a sectional view on the line *w w*, Fig. 6. Fig. 5 is a sectional view on the line *z z*. Fig. 6 is a rear face view of a portion of a door and its casing and my improved lock with a portion of the casing of the latter removed. Fig. 7 is a rear face view of the lock, showing the positions of the parts after one key has been inserted. Fig. 8 is a similar view showing the positions of the parts with both keys inserted and all the bolts withdrawn. Fig. 9 is a detail view illustrating the supplemental bolts and the plate in which they are mounted. Fig. 10 is a view showing the various locking-arms. Fig. 11 is a view showing lever and locking-arm. Fig. 12 is a detail view of the rear or inner face-plate of the lock-casing. Figs. 13 and 14 are detail views of the two keys for operating the lock shown in the other figures.

A represents the front of a safe-deposit box and constitutes the frame for the door *B* of the box, said door being hinged to the frame, as at *a*, and is thrown open when unlocked by means of springs *b*.

A lock-casing *C* is fixed in any suitable manner to the inner face of the door *B*, and in said casing a sleeve *1* is revolubly mounted. 55 The rear portion of the sleeve *1* is provided with a spiral groove *2*, and within said sleeve a bolt *3* is mounted to slide longitudinally, the bolt being provided with a pin or screw 60 *4* to enter the spiral groove in the sleeve *1*, and thus impart longitudinal movement to the bolt when the sleeve is turned. The bolt 65 is provided with an angular end *5*, which moves within a similarly-shaped socket in the casing and when the bolt is thrown engages 70 the inner face of the door-frame, as clearly shown in Figs. 2, 3, 6, and 7. Two tumblers 75 *6* are disposed on the sleeve *1*, the tumbler *6* being loosely mounted thereon and the tumbler being secured to said sleeve, so as to turn therewith, by means of a screw *8*. The tumbler *6* is provided with a series of peripheral 80 projections *c*, adapted to enter a series of holes or openings *c'* in a key *D* when the latter is passed through a slot *c*² in the door and 85 made to move tangentially to the tumbler, this movement of the key causing the tumbler to rotate on the sleeve *1*. The tumbler *6* is provided with a lug *9*, normally disposed in line with the key-slot *c*² and adapted to be 90 engaged by the end of the key *D* to start the rotation of the tumbler when the key is inserted. It is important that this normal position should be accurately maintained, and this is accomplished by means of a spring- 95 pressed finger *10*, pivotally mounted in the lock-casing and having a tooth *11* bearing in a groove *12* in the periphery of the tumbler. The bottom of the groove is curved, as shown in Fig. 4, so that slight pressure against the 100 lug *9* on the tumbler by the key will cause the tooth *11* to ride out of the groove *12* as the tumbler begins to turn. The pressure, however, of the spring-pressed finger against the tumbler is sufficient to prevent the accidental displacement of the latter from its normal position. The tooth *11* on the finger 100 serves also to prevent the rotation of the tumbler by any means other than the proper key by engaging a shoulder *13* on the tumbler after the tumbler shall have been turned sufficiently to cause the groove *12* to pass said tooth. Thus if it should be attempted to rotate the tumbler by means of a wire the en-

gagement of the shoulder 13 on the tumbler with the tooth 12 would prevent the tumbler from being turned far enough to effect the operation of the lock. It would be difficult 5 to raise the spring-pressed finger 10 to disengage the tooth 11 from the tumbler by means of a wire; but to further guard against picking the lock by raising said spring-pressed finger with a wire I provided another and 10 independent spring-pressed finger 14, having a tooth 15 to be engaged by another shoulder on the tumbler, so that in order to permit the rotation of the tumbler both of said fingers must be moved away, and said fingers being 15 mounted independently of each other it would be practically impossible to move them both away from the tumbler at the same time with a piece of wire or any device other than a proper key. The spring-pressed fingers 10 and 14 are provided with beveled teeth 16 at their free ends, and these teeth are normally disposed in the path of the key. When a 20 proper key, which will mesh with the peripheral projections on the tumbler, is inserted 25 into the lock, the forward end of the key will engage the teeth 16 and move the fingers 10 14 and their teeth 11 15 away from the shoulders on the tumbler, and thus permit the rotation of the tumbler and the complete insertion of the key.

A key-slot 17 is provided in the door for the insertion of the key E, with which the tumbler 7 coöperates; but said tumbler is normally so disposed as to prevent the insertion of the 30 key, as shown in Fig. 5, and it must be moved to a position such as the tumbler 6 occupies in Fig. 4. For this purpose the fixed tumbler 7 is provided in its side next to the tumbler 6 with a pin 18, entering a groove 19 in the 35 tumbler 6. When the key D is inserted into the lock, the tumbler 6 will be turned freely on the sleeve 1 until the end wall of the groove 19 engages the pin 18 on the tumbler 7, and then during the completion of the throw of 40 the tumbler 6 the tumbler 7 and the sleeve 1 will turn with it, and said tumbler 7 will thus be moved into position to receive the key E. The insertion now of the key 2 will cause the 45 continued rotation of the tumbler 7 and the sleeve, resulting through the medium of the 50 spiral slot 2 and pin 4 in withdrawing the bolt 3. To avoid possibility of picking the lock by rotating the tumbler 7 with a wire or other instrument, spring-pressed fingers 20 55 coöperate with shoulders on the tumbler 7 in the same manner as above described with respect to the fingers 10 14 and the shoulders on the tumbler 6. To further guard against 60 picking the lock, another spring-pressed finger 22 is employed. This finger is provided with a tooth 23 to be engaged by a shoulder on the tumbler 7; but the free end of said finger is bent laterally and provided with a tooth 24, disposed in position to be engaged 65 by the key D when the latter is inserted to turn the tumbler 6.

It will be seen that by means of the devices above described the key E cannot be inserted until the tumbler 7 shall have first been properly set by the rotation of the tumbler 6 by 70 the key D, that the rotation of the tumbler 7 is essential to the withdrawal of the bolt, and that it requires both keys to unlock the tumbler 7 so that it can be rotated.

The rear or inner face-plate 25 of the lock- 75 casing is provided with a series of lugs 26, which enter between the various spring-pressed fingers and maintain them properly spaced apart.

The door B is provided on its inner face 80 above the lock-casing with two guides for the reception of a plate 27, which is maintained in its normal position with one end abutting against the lock-casing by means of a screw 28. The under face of the plate 27 is made 85 with two grooves 29 29, in which two sliding bolts 30 are disposed and adapted to engage the upper portion of the door-frame A at right angles to the bolt 3. The bolts 30 are normally projected by means of springs 31, which 90 bear at one end in sockets in one end of said bolts and at their other ends against the lock-casing C. The plate 27 is provided on its outer face with a series of lugs 32, between which levers 33 34 35 are pivotally supported. 95 The short arm of each lever 33 and 34 projects through slots in the plate 27 and enters notches 36 in the outer side faces of the bolts 30, so that when said levers are turned in one direction on their fulcrums the bolts will be withdrawn. 100 The short arm 37 of the lever 35, which is disposed between the levers 33 and 34, also passes through a slot in the plate 27, and the free end of said short arm 37 is made slightly wider than the thickness of the bead 38, which 105 separates the grooves 29, so as to enter said grooves and notches 38a in the bolts, and thus normally lock both bolts. The levers 33, 34, and 35 project toward the lock-casing C and terminate over the free ends of the spring- 110 pressed fingers 10, 14, and 22. The levers are made with knife-edge under edges, as shown at 40, Fig. 11, to prevent possibility of manipulating them by means of a wire. The levers 33 and 34 are maintained in and 115 returned to their normal positions by the action of the springs 31. The lever 35, which is made wider than the others, is maintained in and returned to its normal position by means 120 of a spring 41.

From this construction and arrangement of parts it will be seen that when the key D is inserted into the lock the tumbler 6 will not only be rotated and the tumbler 7 set to receive the key E, but the end of the key D 125 will engage the levers 33 34 35 and turn them on their fulcrums, thus withdrawing the bolts 30. The insertion then of the key E will effect the withdrawal of the bolt 3, as before explained.

Should it not be desired to employ the auxiliary bolts 30, they, as well as their operat-

ing devices, can be readily removed by removing the plate 27, which carries them.

Slight changes might be made in the details of construction of my invention without departing from the spirit thereof or limiting its scope, and hence I do not wish to limit myself to the precise details herein set forth.

Having fully described my invention, what I claim as new, and desire to secure by Letters

10 Patent, is—

1. In a lock, the combination with a bolt, of two tumblers, one free and the other operatively connected with the bolt, a separate key for each tumbler and means between the 15 tumblers for causing one of them to be moved in position to receive its key when the other one is operated.

2. In a lock, the combination with a casing, of a sleeve in the casing, a bolt passing through 20 the sleeve and operatively connected therewith, a tumbler secured to the sleeve and normally out of position to receive its key, a tumbler mounted loose on the sleeve and adapted to be operated by a separate key, and means 25 between the two tumblers arranged to cause the fixed tumbler to be moved in position to receive its key when the loose tumbler is rotated.

3. In a lock, the combination with a bolt, 30 of two tumblers, one free and the other operatively connected with the bolt, a device for normally locking the last-mentioned tumbler against rotation, and a key for rotating the free tumbler and simultaneously releasing 35 said locking device.

4. In a lock, the combination with a casing, a sleeve mounted therein and a bolt operatively connected with the sleeve, of a tumbler free on the sleeve, a tumbler secured to the 40 sleeve, a separate key for each tumbler, a series of independent spring-pressed locking-fingers normally engaging each tumbler and means between the two tumblers for moving one to position to receive its key when the 45 other tumbler is operated.

5. In a lock, the combination of a tumbler, a bolt operatively connected with said tumbler, an auxiliary bolt, a lever for operating it, a second tumbler, a key for rotating said 50 second tumbler and simultaneously operating the auxiliary bolt to withdraw it, and a separate key for rotating the first-mentioned tum-

bler to withdraw the bolt operatively connected therewith.

6. In a lock, the combination with a main 55 bolt and an auxiliary bolt, of two tumblers, one operatively connected with the main bolt and the other free to rotate, a separate key for each tumbler, means between the tumblers for moving the one connected with the main bolt to position to receive its key when the free tumbler is rotated, and a lever connected with the auxiliary bolt and disposed in the path of the key by means of which the free tumbler is rotated.

7. In a lock, the combination with a bolt and a key, of a tumbler in the path of and controlling the entrance of the key, two pivoted levers located beyond said tumbler, one of said levers normally locking the bolt and the 70 other connected directly with the bolt for withdrawing it, both of said levers being disposed in the path of the end of the key, so that when the key is inserted the bolt will be unlocked by the movement of one lever and then positively withdrawn by the movement of the 75 other lever.

8. In a lock, the combination with a tumbler, a series of bolts and a key for operating the tumbler, of an independent lever for each 80 bolt, all of said levers disposed in the path of the key and a lever for normally locking all the bolts, said locking-lever also disposed in the path of the key.

9. In a lock, the combination with a tumbler, and a key for operating the same, of a sliding bolt, a lever connected with said bolt and having a knife-edge disposed in the path of the key.

10. In a lock, the combination with a tumbler and a key for operating the same, of a sliding bolt, a lever connected with said bolt and having a knife-edge disposed in the path of the key, and a lever normally locking said bolt against movement and having a knife-edge also disposed in the path of said key.

In testimony whereof I have signed this specification in the presence of two subscribing witnesses.

ALAN ROBB FERGUSSON.
